WIRE GOLF TEE

Frank Manino Bono, Sonora, Calif.

Application December 1, 1950, Serial No. 198,714

2 Claims. (Cl. 273—206)

This invention relates to an improved golf tee of the wire type.

A primary object of the invention is to provide a wire tee of novel form which is more resilient, is practically indestructible, is easily insertable into and withdrawable from the ground, and which supports a golf ball in a more suitable manner.

A further object of this invention is to provide a wire tee which is simpler in structure and cheaper to manufacture.

The above and still further objects and advantages of the present invention will become apparent from a consideration of the following detailed description when taken in conjunction with the accompanying drawings, wherein:

Figure 1 is an elevational view of a golf tee constructed according to the present invention, shown supporting a ball and inserted in the ground, the ball and ground surface being shown in phantom lines;

Figure 2 is an enlarged top plan view of the wire golf tee illustrated in Figure 1; and

Figure 3 is an enlarged elevational view showing a pair of wire members prior to being twisted and formed into the golf tee of the present invention; the completed ground-engaging shank portion being illustrated in phantom lines.

Referring in detail to the drawings, the illustrated golf tee of the present invention, generally designated by the reference numeral 10, is preferably fabricated entirely of rustless steel wire of any desired color. The golf tee 10, as clearly shown in Figure 3, is formed of a pair of similar length wires disposed in coextensive, side-by-side relation, the wires 11 and 12 being initially in U-shaped form.

The legs 14 and 15 and 17 and 18 of the U-shaped wires 11 and 12 are twisted about each other from a point adjacent to and spaced from the bight portions 13 and 16 to the free ends thereof so as to form a ground-engaging shank 19 having a pointed lower end 20.

2

As clearly shown in Figure 2, the portions of the legs 14 and 15 of the U-shaped wire 11, intermediate the point where the wires are twisted upon each other and the bight portions 13, are bent to form a substantially circular open loop or seat 21. Similarly, the portions of the legs 17 and 18 of the U-shaped wire 12 contiguous to the bight portion 16 are bent to form a substantially circular open loop or seat 22, Figure 2. The circular seats 21 and 22 are bent into widely upward divergent relation with respect to each other to cooperate in forming a saddle, generally designated by the reference numeral 23, for receiving a golf ball. As clearly shown in Figures 1 and 2, the saddle-forming seats 21 and 22 project laterally outwardly from opposite sides of the ground-engaging shank 19.

Although only one embodiment of the wire tee of the present invention has been described, it is readily apparent that numerous modifications can be made without departing from the spirit of the invention as set forth in the appended claims.

What I claim is:

1. In a golf ball tee, a pair of wires having circular bight portions and legs at opposite ends of said bight portions, the legs of the two wires being twisted upon each other to define a shank portion terminating in a point adapted to be inserted into the ground, with the bight portions projecting laterally outwardly from opposite sides of the shank portion at the end thereof remote from the point so as to define a golf ball-receiving saddle.
2. In a golf ball tee, a pair of wires having terminal end portions and intermediate portions, said terminal end portions being twisted upon each other so as to define a shank having a free end for insertion in the ground and another end from which said intermediate portions extend, said intermediate portions being open loops which extend laterally from opposite sides of the shank in widely divergent relation to each other so as to provide seats for supporting opposite side portions of the underpart of a golf ball rested upon the seats.
